Administrator:

UNITED STATES PATENT OFFICE.

TIMOTHY HOLLAND, OF CHICAGO, ILLINOIS, ASSIGNOR TO MARY C. HOLLAND,
OF SAME PLACE.

DESIGN FOR A RADIATOR.

SPECIFICATION forming part of Design No. 25,975, dated August 25, 1896.

Application filed July 25, 1896. Serial No. 600,555. Term of patent 14 years.

To all whom it may concern:

Be it known that I, TIMOTHY HOLLAND, a citizen of the United States, residing at Chicago, in the county of Cook and State of Illinois, have invented and produced a new and original Design for Radiators, of which the following is a specification, reference being had to the accompanying drawings, showing the same.

10 Figure 1 is a perspective side elevation of a radiator, showing my design; and Fig. 2 is an enlarged horizontal section taken through a pair of the radiator-loops for the purpose of showing more distinctly their exterior configuration, these views being deemed necessary to fully illustrate my design.

15 The leading feature of my design consists in a concave scallop formed in the front quarter upon each side of the radiator-loops 20 and extending along their entire length.

A is the loop, which is ovate in cross-section in its general contour.

a is the front quarters.

a' is a concave scallop extending from the top of each loop down to the bottom, presenting to the eye the combined effect of a reversed curved surface in each front quarter of the several members of the loop. The top and base of the radiator are provided with ornamentation in the usual manner, which 25 is extended obliquely across the scallop a'. 30

What I claim is—

The design for radiators substantially as described and shown in the accompanying drawings.

TIMOTHY HOLLAND.
